FIG. 4.

UNITED STATES PATENT OFFICE

2,045,368

EARTH BORING DRILL

Earl A. Reed, Garber, Okla.

Application May 18, 1934, Serial No. 726,383

16 Claims. (Cl. 255—71)

This invention relates to improvements in earth boring drills and more particularly to improvements in boring drills of the roller cutter type.

5 One object of the invention is to provide an improved means for mounting a roller cutter upon a drill bit body so as to provide for relative rotation therewith and to prevent accidental separation of the cutter from the bit body.

10 Another object of the invention is to provide an anti-friction bearing for the roller cutter which is capable of withstanding the severe service to which a bit of this type is subjected.

Another object of the invention is to provide 5 a stronger means for attaching a bearing member which carries the roller cutter to the bit body so as to prevent separation of the cutter and bearing member assembly from the bit body during operation of the bit.

20 Another object of the invention resides in the provision of anti-friction roller bearing members which are effective to prevent separation of the roller cutter and the bearing member upon which it is mounted.

25 Another object of the invention is to provide a means for retaining grease, packed between the interior of the cutter shell and exterior of the bearing member, which means is effective to retain grease in the bearing spaces during the 30 operation of the bit in a well.

A still further object of the invention is to provide a high pressure slush chamber in the drill head or body which has a plurality of high velocity outlets leading therefrom.

35 Other objects and advantages of the invention will appear in the following specification of the preferred embodiment of the invention which is shown in the attached drawings of which:

40 Figure 1 is an elevation of the bit head body partly in section;

Figure 2 is a partial sectional view of the bit head taken on line 2—2 of Figure 1;

Figure 3 is an elevation of the bit head looking toward the left in Figure 1;

Figure 4 is a sectional view taken on line 4—4 of Figure 1, and with the cutter and bearing member assembly removed;

Figure 5 is a side elevation of the bearing member upon which the cutter is mounted;

Figure 6 is another view of the bearing member taken in a direction indicated by the line 6—6 of Figure 5;

Figure 7 is a perspective of the lug plate which 55 locks the bearing member to the bit head spindle.

Referring more particularly to the drawings, 10 indicates the bit head body which is provided at its upper end with a threaded box portion 11 to receive a drill pipe. The bit head 10 is provided at its lower end with diametrically opposed spindles 12 which receive roller cutter assemblies 13 comprising bearing members 14, roller cutters 15, and roller bearings 16 and 17.

It is noted that the bit is provided with two 10 diametrically opposed roller cutter assemblies mounted upon individual spindles 12 such that inner exterior elements of the roller cutter 15 are substantially in vertical abutting relationship. Since the two roller cutter assemblies and their associated spindles are identical in construction, only one assembly and spindle will be described.

The drill bit body 10 is provided on its lower portion with projections 18 upon which the spindles 12 are formed integrally therewith and on 20 the lower portion thereof. As shown in Figure 2, the spindle 12 is substantially elliptical shaped in horizontal cross section with the ends of the ellipse flattened to provide a spindle with flat 25 side surfaces 19. The area of the cross section of the spindle is less than the area of the horizontal cross section of the projections 18, as shown in Figures 1 and 2. That is, the projections 18 are recessed inwardly to form the spindle 12 so as to provide a surface which is normal 30 to the axis of the bit head against which the bearing member 14 and the lug plate 21 abut, as will be hereinafter described. The lower end of the spindle is provided with a frusto-conical 35 surface 20, the opposed elements of which are disposed in substantially right angular relation, with the lower element perpendicular to the axis of the bit head and the inner element parallel to said axis.

The bearing member 14 is provided with an interior frusto-conical surface 22 which is adapted to register with and fit the exterior frusto-conical surface 20 of the spindle. As shown in Figures 5 and 6, the exterior surface of the bearing member is in general frusto-conical and is provided with bearing races 23 and 24 to receive roller bearings 16 and 17, respectively, (Figure 1). The bearing races 23 and 24 are separated by an annular flange 25 having a bearing surface 45 abutting the roller bearings 16 to form a thrust bearing for the roller cutter, as shown in Figure 1. The smaller end of the bearing member 14 has the form of an annular flange 25a which 50 has a bearing face presented to the roller bear- 55

ings 17 and which also acts as a thrust bearing to retain the cutter 15 on the bearing member.

The roller cutter 15 is formed with an internal surface or generally frusto-conical formation.

- 5 This surface is likewise provided with bearing races 26 and 27 to receive roller bearings 16 and 17. The bearing races 26 and 27 are also separated by an annular flange 28 having a bearing surface abutting the ends of the roller bearings 17 to form part of the thrust bearing above referred to. The base end of the frusto-conical roller cutter 15 is provided with an internal annular flange 29 to retain the roller 16 in position, and this flange is further provided with an annular recess 30 which receives an annular flange 31 provided near the base of the bearing member 14 in bearing engagement to provide a grease seal between the roller cutter and the bearing member. It is to be noted that the elements of the 20 circumferential face of this flange are parallel to the axis of the cutter so that the cutter may be assembled upon the bearing member by a motion parallel to the axis of the cutter. The flange 29 also has a bearing face abutting the roller bearings 16 which also forms a thrust bearing to retain the roller cutter upon the bearing member 14.

The roller bearings 16 and 17 are of tapered formation and the bearing races of the bearing member 14 and cutter 15 have surfaces of frusto-conical formation in rolling contact with the tapered surface of the roller bearings. These frusto-conical surfaces of the bearing races 23 and 26 of the bearing member and the roller cutter respectively, have a common apex, by projection, substantially coincident with the apex of the frusto-conical external surface of the roller cutter. The similar frusto-conical surfaces of the bearing races 24 and 27 are of different angularity than the surfaces of bearing races 23 and 26 and have a common apex which is coincident with the axis of the roller cutter, but which is spaced from the apex of the external frusto-conical surface of the roller cutter in order that the two sets of roller bearings 16 and 17 may more efficiently transmit the different stresses to which they are subjected.

In order that the roller bearings 16 and 17 may be placed within the bearing races, the bearing member 14 is provided with bores 32 and 33 through which the roller bearings are inserted into the bearing races. When the device is assembled, those bores 32 and 33 are closed by plugs, one of which is shown at 34 in Figure 1. These plugs 34 are sections of the bearing member and have inner surfaces registered with frusto-conical surface 20 of the spindle and outer surfaces registering with the bearing surfaces of the bearing races 23 and 24.

In manufacture the bearing member 14 is brought roughly to form, the bores 32 and 33 are drilled, the sections 34 are then inserted, and the bearing member machined to final form. The sections 34 are then removed and the cutter 15 and bearing member 14 placed in assembled relation. The rollers 16 and 17 are then inserted and the bearing races packed with grease, after which the sections 34 are again inserted and welded into place as indicated at 35. A final machining of the interior surface of the bearing member 14 may then be necessary. This roller bearing cutter and bearing member assembly may be furnished as a complete article of manufacture supplied to drill operators to be installed upon a bit head. It is noted that there is no rela-

tive movement between the spindle 12 and the bearing member 14, and that all wear takes place within the replaceable cutter and bearing member assembly.

To secure the bearing member to the spindle a 5 lug plate 21 is provided with lugs 36 which engage with the notches 37 provided in extending portions 38 of the bearing member 14, which portions extend laterally from the spindle 12 beyond the roller cutter when the bearing member and 10 cutter assembly is positioned upon the spindle. The lug plate 21 partially surrounds the spindle 12 and closely fits the spindle, as shown in Figure 2. The lower edge 37a of the lug plate 21 is formed to closely fit the internal frusto-conical surface 22 of the bearing member 14 and may be assembled with the bearing member by a movement parallel to the axis of the lugs, 36. In practice, the lug plate is assembled with the bearing member before placing the same upon 20 the spindle and is welded to the bearing member along the lower edge 37a of the lug plate, as indicated at 38a, Figure 1. The lug plate 21 may be assembled with the bearing member and cutter assembly to form a complete article of manufacture which may be furnished to drill operators as above indicated. This assembly, including the lug plate, may be placed upon the bit head by a movement parallel to the axis of the bit head body.

The lug plate 21 is provided with a tapered bore 39 which registers with a screw threaded bore 40 in the spindle 12 when the lug plate is in position upon the spindle. A screw threaded plug 41 having an enlarged tapered head is 35 screw threaded into the bore 40 to lock the lug plate along with the bearing member and cutter assembly 13 upon the spindle 12. It is to be noted that all portions of the spindle 12 are positioned in a direction axially of the drill head, 40 with respect to the base area of the spindle, which area is defined by the intersection of said spindle with the projection 18 of the drill head. That is, the spindle is not undercut at any place and there is no localized stress adjacent the operation of the drill. Also, as shown in Figure 1, the upper edge of the lug plate 21 and the edge of the bearing member 14 in contact with the projection 18 of the drill head form a force transmitting surface abutting the projection 18 of 50 the drill head. This construction provides for transmitting a large portion of the forces to which the roller cutter is subjected directly to the massive body of the drill head independently of the spindle.

As shown particularly in Figure 4, drill head 10 is hollow and is formed with an inverted T-shaped chamber 42 which is in communication with the interior of the threaded box 11 which 60 communicates with the interior of a drill pipe (not shown) through which a circulating fluid is supplied to the drill head. The chamber 42 communicates with the exterior of the drill head through opposed bores 43 closed by screw threaded plugs 44 in order to allow cleaning of the interior of the drill head in the event that it becomes clogged with solid matter in the circulating fluid. The lower portion of the drill head is provided with a plurality of spaced bores 45 connecting the chamber 42 with the exterior of 70 the drill. Preferably, the bores 45 are screw threaded and pipe nipples 46 inserted therein to prevent wear upon the drill head body 10, due to abrasives in the circulating fluid which will normally unduly enlarge the bores through 75

which the fluid is injected into the drill hole. The pipe nipples may be cheaply and quickly replaced when they become worn by the circulating fluid. Also the pipe nipples afford a means 5 for directing a portion of the circulating fluid to the gauge mark of the hole being drilled for cleaning the bottom of the hole in advance of the gauge cutting teeth and also for cutting and washing loose from the matrix the softer formations. The portions of the nipples extending beyond the bottom of the drill head may be extended so as to be as near to the bottom of the hole during operation as desired for efficiency in washing the bottom of the hole and cutting 10 formations or strata.

While I have shown and described the preferred embodiment of my invention, it is to be understood that the present invention is not to be limited to the precise details of construction 20 herein shown and described. It is therefore my intention that the scope of my invention be unrestricted other than by the appended claims.

I claim as my invention:

1. In a device of the character described, the 25 combination with a drill head having a vertically disposed cutter supporting spindle with a frusto-conical surface at its lower end, of a bearing member having substantially frusto-conical external and internal surfaces, the latter surface being adapted to engage the frusto-conical surface of said spindle, a roller cutter having substantially frusto-conical bearing surfaces, said bearing member having a plurality of raceways formed in the external surface thereof and said 30 roller cutter having a plurality of complemental raceways in the internal surface thereof, anti-friction rollers disposed within said complemental raceways for preventing longitudinal movement of said bearing member and said roller cutter relative to each other and providing for relative rotation with respect to each other, means carried by said bearing member and embracing said spindle for locking said bearing member and spindle against relative rotation, and means to 35 lock said bearing member and spindle in assembled relation.

2. In a device of the character described, the 50 combination with a drill head having a vertically disposed cutter supporting spindle with a frusto-conical surface at its lower end, of a bearing member having substantially frusto-conical external and internal surfaces, the internal surface of said bearing member being adapted to engage the frusto-conical surface of said spindle and the external surface of said bearing member being formed with a plurality of annular channels surrounding it, a roller cutter having an internal substantially frusto-conical surface, said cutter having a plurality of annular channels formed 55 in the internal surface thereof adapted to register with the plurality of annular channels formed in the external surface of said bearing member, anti-friction rollers disposed in said 60 registering channels across the joints thereof, said bearing member being provided with apertures through the frusto-conical surfaces thereof to provide for the introduction of said anti-friction rollers into said registering channels, sections of frusto-conical bearing members adapted to close said apertures to register with the 65 external and internal surfaces of said bearing member, means on said bearing member adapted to interlock with said spindle whereby rotation of said bearing member with respect to said

spindle is prevented, an annular projection formed on the external frusto-conical surface of said bearing member, said cutter having an annular depression formed in the internal frusto-conical surface thereof adapted to receive said annular projection in grease sealing engagement therewith, and interlocking means between the means on said bearing member and spindle to prevent axial separation of said spindle and bearing member, said means including 10 a pin having a head disposed in a bore through said means on said bearing member and engaging said spindle by means of screw thread.

3. In a device of the character described, the combination with a drill head having a vertically disposed cutter supporting spindle with a frusto-conical surface at its lower end, of a bearing member having substantially frusto-conical external and internal surfaces, the latter surface being adapted to engage the frusto-conical surface of said spindle, a roller cutter having a substantially frusto-conical internal surface, said bearing member having a plurality of raceways formed in its external surface, said roller cutter having a plurality of complemental raceways formed in its internal surface, anti-friction rollers disposed within said complemental raceways for preventing longitudinal movement of said bearing member and said roller cutter relative to each other while providing for relative rotation with respect to each other, the frusto-conical walls of the bearing member extended outwardly beyond the interior of the cutter and having notches formed therethrough adjacent the outer margin of said bearing member, a lug member 20 formed to seat on the interior of said bearing member and provided with means interlocked with said notches, said lug member having portions thereof welded to said bearing member, the interior of said lug member being adapted to snugly fit an exterior surface of said spindle and to be mounted thereon by sliding the same in a direction parallel to the vertical axis of said spindle, and means to interlock said lug member 25 and said spindle against relative movement.

4. In a device of the character described, the combination with a drill head having a vertically disposed cutter supporting spindle with a frusto-conical surface at its lower end, of a bearing member having substantially frusto-conical external and internal surfaces, the latter surface being adapted to engage the frusto-conical surface of said spindle, a roller cutter having a substantially frusto-conical internal surface, said bearing member and cutter having a plurality of complemental raceways in the form of tapered annular channels formed in the external surface of said bearing member and in the internal surface of said roller cutter, anti-friction rollers disposed within said complemental raceways, for preventing longitudinal movement of said bearing member and said roller cutter relative to each other while providing for relative rotation with respect to each other, the frusto-conical walls of the bearing member extended outwardly beyond the interior of the cutter, slots formed through the frusto-conical walls of the bearing member adjacent its outer margin, a lug member 50 formed to seat on a segment of the interior of said bearing member and provided with means adapted to interlock with the aforesaid slots or notches formed through the frusto-conical walls of the bearing member, means to fasten said lug 55 member to the bearing member.

member to said bearing member in interlocked relation, the interior of said lug member being adapted to snugly fit an exterior surface of said spindle and to be mounted thereon by sliding 5 the same in a direction parallel to the vertical axis of said spindle, said spindle being recessed inwardly from the margin of the drill head so as to leave a flat surface on said drill head, the top of said lug being seated against said 10 flat surface so as to be supported thereby, said bit head having provided thereunder a shoulder, having a face at right angles to the vertical axis of the spindle, the top of the inner wall of the bearing member being flattened to fit said shoulder and seated thereon to be supported thereby, and means coacting with the lug of the bearing member and said spindle to maintain them free 15 from relative axial movement.

5. As an article of manufacture, a bearing 20 member having an internal frusto-conical surface, said bearing member having apertures through the frusto-conical surface, said apertures being spaced from the apex of said conical surface, and closures for said apertures having surfaces registering with said frusto-conical surface.

6. As an article of manufacture, a bearing 25 member having internal and external frusto-conical surfaces tapering in similar directions, the external frusto-conical surface being formed with raceways in the form of tapered annular channels, the bearing member having apertures formed through the frusto-conical surfaces and opening into said raceways, and closures for said 30 apertures having surfaces registering with the internal surface of said bearing member and the bearing surfaces of said raceways.

7. In a drill, the combination with a drill head 35 of a bearing member secured thereto having an internal frusto-conical surface and a plurality of external frusto-conical surfaces tapering in the same general direction but of different angularity, an annular flange projecting from the external surface of said bearing member and adapted 40 to serve as a thrust bearing for anti-friction roller bearings, a roller cutter having a plurality of internal frusto-conical surfaces tapering in the same general direction but of different angularity, said roller cutter having an annular 45 channel formed in the internal surface thereof receiving said annular flange, said annular flange being disposed within said channel but incompletely filling the same, anti-friction roller bearings disposed within the remainder of said channel and abutting said flange and a wall of said 50 channel to prevent axial separation of said roller cutter and said bearing member, said bearing member having an aperture therethrough opposite said channel providing means for introducing said anti-friction roller bearings into 55 said channel, and a section of bearing member having surfaces registering with the external surface of said bearing member closing said aperture and fastened to said bearing member.

8. In a drill, the combination, with a drill head 60 of a bearing member secured thereto having a plurality of external frusto-conical surfaces tapering in the same general direction, but of different angularity, an annular flange projecting 65 from the external surface of said bearing member and adapted to serve as a thrust bearing for anti-friction roller bearings, a roller cutter having a plurality of internal frusto-conical surfaces tapering in the same general direction, but of different angularity, said cutter having an an-

7
nular groove formed in the internal surface thereof receiving said annular flange, said annular flange being disposed within said groove but incompletely filling the same, anti-friction roller bearings disposed within the remainder of said groove and abutting said flange and a wall of said groove to prevent axial separation of said roller cutter and said bearing member, said bearing member having an aperture through said bearing member opposite said groove providing 10 means to introduce said anti-friction roller bearings into said groove, and a section of bearing member having surfaces registering with the external surface of said bearing member closing said aperture and fixed in position in said bearing member.

9. As an article of manufacture, a bearing 15 member having a plurality of external frusto-conical surfaces tapering in the same general direction, but of different angularity, an annular flange projecting from the external surface of said bearing member and adapted to serve as a thrust bearing for anti-friction roller bearings, said bearing member having an aperture therethrough spaced from its apex, and a section of 20 bearing member closing said aperture and having an external surface registering with the external surface of said bearing member which extends circumferentially from said aperture.

10. As an article of manufacture, a roller cutter 25 having a plurality of internal frusto-conical surfaces tapering in the same general direction, but of different angularity, said roller cutter having an annular channel formed in the internal surface thereof adapted to receive anti-friction roller 30 bearings and a thrust bearing member for one end of said roller bearings.

11. In a drill, the combination with a drill head 35 of a cutter assembly comprising a roller cutter member having an external substantially frusto-conical surface and a plurality of internal frusto-conical surfaces tapering in the same general direction, but of different angularity, one of which said internal frusto-conical surfaces, by projection, having its apex substantially coincidental 40 with the apex of the external frusto-conical surface of the roller cutter, an annular flange bounding the base end of said frusto-conical surface and adapted as a thrust bearing for anti-friction 45 rollers, and a bearing member having a plurality of external frusto-conical surfaces tapering in the same general direction, but of different angularity, one of which said frusto-conical surfaces, by projection, having its apex substantially coincidental 50 with the apex of the external frusto-conical surface of the roller cutter within which it is disposed, said last named frusto-conical surface being opposite and complementary to the like surface in said roller cutter, and spaced apart therefrom, an annular flange bounding the apical end 55 of said frusto-conical surface of said bearing member and adapted as a thrust bearing for anti-friction rollers, anti-friction rollers disposed within the space between said complementary frusto-conical surfaces and abutting both of said 60 flanges, one of said members having an aperture therethrough to provide means for inserting anti-friction rollers into said space, a plug closing said hole having an end completing the frusto-conical surface of the member through which 65 said hole extends, and means for fastening said plug in fixed position.

12. The combination described in claim 11, in 70 which said roller cutter is provided with an annular groove in the internal surface thereof, and 75

- 5 said bearing member is provided with an opposite and complementary groove, the bottom of each of said grooves being frusto-conical in form and having the bases thereof extending in the same direction as the bases of the members in which they are formed, and disposed so that their apexes, by projection, are not coincidental with the apex of the external surface of the roller cutter enclosing them, tapered roller bearings disposed within and substantially filling said grooves to prevent axial movement of said roller cutter and said bearing member relative to each other, one of said members having an aperture to provide means for inserting roller bearings into said 10 grooves, a closure for said aperture and means to fix said closure in position.
- 10 13. In a cutter assembly, the combination of a bearing member and a roller cutter member, both having substantially internal and external frusto- 15 conical surfaces, the internal surface of the cutter member and the external surface of the bearing member having bearing engagement with each other, a plurality of raceways between said members adapted to receive tapered roller bearings 20 to prevent axial movement of said members relative to each other while providing for free rotation of said members relative to each other, a set of tapered roller bearings disposed within each said raceway, one of said sets of said tapered 25 bearings so disposed that the apex of each tapered roller thereof by projection is substantially coincidental with the apex of the external surface of the roller cutter, and another set of said tapered roller bearings so disposed that the apex 30 of each tapered roller thereof, by projection, is not substantially coincidental with the apex of the external surface of the roller cutter, and means providing for inserting said tapered roller bearings and holding them in raceways.
- 35 14. In a rotary drill, a drill head body having a spindle projecting therefrom, the projecting end
- 5 of said spindle being formed with an external frusto-conical surface, a bearing member for rotatively supporting a rotary cutter, said bearing member having an interior frusto-conical surface engaging the frusto-conical surface of said spindle, a locking member for retaining said bearing member upon said spindle, said locking member engaging a portion of said interior frusto-conical surface and said drill head body for transmitting a portion of the stress to which said bearing member is subjected during drilling directly from said bearing member to said drill head body.
- 10 15. In a rotary drill, a rotary cutter member rotatively journaled upon a bearing member, said bearing member being provided with integral annular flanges upon its outer surface defining a bearing race for receiving roller bearings, said rotary cutter member being provided with integral annular flanges upon its inner surface defining a bearing race complementary to said first mentioned bearing race for receiving said roller bearings, said roller bearings coacting with said annular flanges to prevent axial separation of said members, one of said members having an aperture through the bearing surface of its bearing race to provide for insertion of said roller bearings, and a closure for said aperture having a bearing surface registering with said bearing surface.
- 15 16. In a drill having a drill head, the combination of a support depending from said drill head, a removable cutter support surrounding said depending support, a cutter rotatably mounted thereon and having its axis of rotation at an angle to the direction of removal of said cutter support, means to prevent relative rotation and separation of said supports, and means to prevent axial separation of said cutter and said cutter support.
